UNITED STATES PATENT OFFICE

EUGENE R. KULKA, OF NEW YORK, N. Y., ASSIGNOR TO C. D. WOOD ELECTRIC CO. INC.,
OF NEW YORK, N. Y., A CORPORATION OF NEW YORK

FLUSH PLUG RECEPTACLE AND METHOD OF MANUFACTURING THE SAME

Application filed February 9, 1928. Serial No. 253,118.

My invention relates to a new and improved flush plug receptacle and a new and improved method of manufacturing the same.

One of the objects of my invention is to provide a flush receptacle comprising a body made of bakelite or other phenol condensation product, or other material which is formed under heat and pressure, said body having a supporting strap imbedded therein and projecting therefrom, said strap and body being integrally united by the molding process. However, my invention is not limited in certain aspects thereof, to a body which is molded integral with the supporting strap, or to a one-piece body made of a coherent mass of molded material.

Another object of my invention is to provide a device of this type which is simple and economical to manufacture and which shall be efficient and durable.

Other objects of my invention will be set forth in the following description and drawings which illustrate a preferred embodiment thereof, it being understood that the above general statement of the objects of my invention is intended to generally explain the same and not to limit it in any manner.

Fig. 1 is a top view of a plug receptacle body and strap.

Fig. 2 is a bottom view of Fig. 1.

Fig. 3 is a view similar to Fig. 2, the contacts being omitted.

Fig. 4 is a sectional view on the line 4—4 of Fig. 2.

Fig. 5 is a perspective view showing a contact.

Fig. 6 is a plan view of the supporting strap.

Fig. 7 is a side view of the supporting strap.

Fig. 8 is a detail sectional view showing how the plug receptacle body and the contact are connected or assembled.

Fig. 9 is a sectional view of the insert shown in Fig. 8.

Fig. 10 is a side elevation of the completed article.

Fig. 11 is a bottom view showing how a bottom insulating member is connected to the body of the receptacle.

Fig. 12 is a view similar to Fig. 1 illustrating a duplex receptacle.

Fig. 13 is a bottom view of the device shown in Fig. 12.

Fig. 14 is a view similar to Fig. 13, the contacts being omitted.

Fig. 15 is an inverted side view of the device shown in Fig. 12.

Fig. 16 is a sectional view on the line 16—16 of Fig. 13.

Fig. 17 is a sectional view on the line 17—17 of Fig. 13.

Fig. 18 is a perspective view of a contact.

Fig. 19 is a plan view of the supporting strap.

Fig. 20 is a side view of the strap shown in Fig. 19.

Fig. 21 is a sectional view on the line 21—21 of Fig. 22.

Fig. 22 is a central section through the mold utilized for making articles of this type.

The device comprises a body portion 1 which is preferably made of bakelite or other phenol condensation product having a supporting strap 2, a part of which is imbedded in the said body 1, the ends of the strap 2 projecting from the body 1. As shown in Fig. 6 the strap 2 is provided with an intermediate bridge portion 3 which is narrower than the main body of the strap 2, so that the strap 2 can extend continuously through the body 1 while the contacts may be located in the recesses 4 and 5 of the strap 2, so that the contacts are separated from the strap 2 by the insulating material of which the body 1 is formed.

Since the receptacle illustrated herein is of the universal type, it is provided with four longitudinal recesses 6, 7, 8 and 9. The contacts C have the configuration shown in Fig. 5 and they are provided with contact wings or portions C' and C''. Hence and as shown more particularly in Fig. 2, the wings C' of the two contacts C are located in the corresponding recesses 6 and 8, and the wings C'' of said contact C are located in the other pair of corresponding recesses 7 and 9. The wings C'' are adapted to cooperate with a plug of the tandem type, and the wings C' are adapted to cooperate with the plug of the parallel type.

so that either type of plug may be used with the plug receptacle illustrated.

Plug receptacles of this kind are designated as the "universal" type with the trade.

As shown in Fig. 8, inserts 10 preferably having knurled exteriors are connected to the receptacle 1 after the molding so that no separate fastening means are required to hold the said inserts 10 in position. The knurled exterior of the inserts 10 is to prevent them from turning. The same purpose could be fulfilled by having the exterior peripheries of said inserts polygonal. The inserts 10 are internally threaded so as to enable the terminal screws 11 to be suitably held in position. As shown in Fig. 9, each insert 10 is originally provided with a reduced upper portion projecting from the receptacle body. As shown in Fig. 5, each contact C has a perforation which is adapted to fit over the reduced end of one of the contact inserts 10, and this reduced end is then enlarged by being spun over so as to act like a rivet and firmly clamp the contact C in position.

The bottom of the receptacle is provided with a central longitudinal recess 12 and a disc 14 made of any suitable insulating material is connected to the underside of the receptacle body 1 by means of a tapered rivet 15 which has a drive fit so that the insulating cover 14 is firmly held in position. It will be noted in Fig. 4 that the recess 12 extends substantially to the bridge portion 3 of the strap 1.

In order to manufacture the article previously described, molds of the type used for forming bakelite are employed.

A solid cartridge or tablet of bakelite corresponding to that part of the receptacle body 1 which is shown as located above the strap 2 in Fig. 10, is placed on the bottom of the lower mold member.

For convenience that part of the receptacle body which is shown as being located above the strap 2 in Fig. 10, will be designated as the top of the device, although the operation of the device is of course not dependent upon the position in which it is held. The strap 2 is now placed in proper position upon this tablet or cartridge, the ends of said strap 2 projecting beyond the top of the lower mold member. An imperforate tablet or cartridge corresponding to the lower portion of the device is now placed upon the strap 2.

An upper mold member is now forced down upon the masses of bakelite and this upper mold member is provided with pins corresponding to the four longitudinal openings 6, 7, 8 and 9 and the central recess 12. The punch exerts a pressure of about three thousand pounds per square inch of molding surface and the bakelite is subjected to this pressure, and the proper molding temperature, for a suitable period, namely, for about 2½ to 3 minutes. During this molding operation

the preformed masses of bakelite powder shrink so that the preformed article is from one and a half to twice the size of the finally completed article. The bakelite powder from which the tablets have been made first becomes plastic and then sets. Since the plane of the strap 2 is substantially perpendicular to the central longitudinal axis of the body 1, and since that part of strap 2 which is to be imbedded in the bakelite body is not subjected to direct contact with the upper mold member, it can be readily held in suitable position during the intermediate stage, namely, while the bakelite is shrinking and setting, due to the heat and pressure.

After the bakelite has been set due to the heat and pressure, it continues to shrink until it has thoroughly cooled. Hence, after the molding has been completed, the inserts 10 can be forced into suitable recesses which have been formed in the bakelite body by pins located on the upper mold member (and additional to those previously mentioned). The inserts are forced in so as to have a drive fit before the molded receptacle bodies have thoroughly cooled and the shrinkage of said receptacle bodies 1 due to said cooling, causes the inserts to be very firmly held in position. The contacts C are then mounted in proper position and the assembly of the article is completed.

The receptacle body 1' is similar to the body 1 previously described save that it consists of two wings or portions connected by an intermediate portion also made of bakelite and molded in one piece with the end portions. The strap 2' illustrated in Fig. 19 is also partially imbedded in both halves of the flush receptacle body 1' and it is provided with a series of openings R for clearing the contact members which are located in the longitudinal openings of the receptacle. The strap 2' is provided with a central tapped or internally threaded opening T which is located in the bridge portion of the receptacle so that the strap can be readily connected to the cover plate of the outlet box without requiring the use of an additional insert or inserts for this purpose.

The inserts 10 and the screws 11 are similar to those previously described. The contacts 20 are of the same general type as the contacts C previously described save that each contact 20 is provided with four contact wings, 21, 22, 23 and 24 which are disposed as shown in Fig. 13. A second contact 20 is also provided, the standard arrangement of the contact wings being illustrated in Fig. 12. The molding operation is shown in detail in Figs. 21 and 22. The lower part M of the mold is of sufficient depth to hold the bottom bakelite cartridge and the projecting ends of the strap 2 are located upon the top of this bottom member M. The strap 2 is preformed into the shape shown in Fig. 22

before it is assembled with the body of the receptacle. The second bakelite cartridge or tablet is then placed in position and the upper mold member M' is caused to descend by 5 a suitable hydraulic press. This upper mold member is provided with a series of projecting pins P which form the various recesses and openings in the completed receptacle. These pins P are shown as broken away in Fig. 22 10 in order to illustrate the device more clearly. Hence the central portion of the strap 2, which is completely imbedded within the bakelite body is not subjected to direct contact with either the members M or M', but 15 the projecting ends thereof are firmly clamped in position between the members M and M'. This operation is rendered possible by the fact that the plane of the strap is perpendicular to the central longitudinal axis 20 of the body 1'. The bottom of the receptacle 1' is provided with a cover 14 which is also held in place by means of a rivet 15 having a drive fit. The central pin P of the mold M', which forms the central recess 12 is prefer- 25 ably made long enough to abut the corresponding part of the strap 2.

Hence the underside of the strap is exposed so that the internal thread can be readily formed. The top of the strap corresponding 30 to the bridge portion of the receptacle body is covered with only a very thin layer of bakelite and this layer of bakelite may be omitted if desired, as it serves no useful purpose.

I have shown a preferred embodiment of 35 my invention, but it is clear that numerous changes and omissions can be made without departing from the spirit of my invention.

I claim:

1. In combination, a flush receptacle body 40 made of moldable material, a metal supporting strap, a continuous portion of which is imbedded in said body, said strap being molded integral with said body, and having its plane substantially perpendicular to the central longitudinal axis of said body, said strap also having portions projecting beyond said body, said body having four contacts substantially equal in distance from each other and substantially parallel to the longitudinal 45 axis of the said body, said contacts being located in cut-out portions of the said strap, so that said contacts are spaced from said strap by the insulating material of which the said body is composed.

50 2. In combination, a flush receptacle body made of moldable material, a metal supporting strap, a continuous portion of which is imbedded in said body, said strap being molded integral with said body, and having its plane substantially perpendicular to the central longitudinal axis of said body, said strap also having portions projecting beyond said body, said body having four contacts substantially equal in distance from each other and substantially parallel to the longi- 55

tudinal axis of the said body, said contacts being located in cut-out portions of the said strap, so that said contacts are spaced from said strap by the insulating material of which the said body is composed, that portion of said strap which is imbedded in said body including a narrow diagonal metal strip inclined to the longitudinal axis of the strap. 70

In testimony whereof I affix my signature.
